DRAGLINE BUCKET

William A. Luce, Portland, Oreg., assignor of five per cent to Harry A. Bell and five per cent to John A. Dodok, both of Linnton, Oreg.

Application August 30, 1934, Serial No. 742,065

5 Claims. (Cl. 37—125)

My invention is primarily intended for use in the handling of finely divided precious metal bearing substances such as sand, gravel, ocean beach sand and the like.

5 The invention is comprised primarily of a roller supported fabricated frame having two or more wheels disposed at either side of the frame and having one or more drums disposed at each of the oppositely disposed ends of the frame. A runner is disposed below the frame and runs longitudinally and at either side of the frame. The runners are disposed below the sides of the frame.

15 A tiltable bucket is disposed within the frame and it is disposed between the sets of wheels and drums. A door is disposed at the filling end of the bucket and a breather door is disposed at the rear end of the bucket. A main pull line is secured to the front end of the bucket and is attached thereto by suitable hitching means. The main pull lines pass through suitable guideways disposed upon the front end of the frame and the same are so located that a crowding action is imparted to the bucket during the period of pull in which the bucket is being filled with materials. A haul back line is disposed at the rear of the bucket. The haul back line is secured directly to a bridle and in the hauling back of the assembled device the breather door and the door disposed at the front end of the bucket are preferably in a closed position.

20 A trip line is also secured to the bridle to which the haul back line is attached. The purpose and object of the trip line is to open the respective doors and to place the bucket in position for being filled and for raising the frame and drums clear of the surface in order that the bucket may ride directly upon the media from which the material is to be dug and placed within the bucket.

25 To facilitate the tripping of the bucket I provide line supporting eyes in either side and at either end of the bucket to which any suitable sling may be attached of sufficient dimension and strength to facilitate the raising of the entire assembled device when filled to facilitate the releasing of the materials therefrom through the action of gravity.

30 The primary object of my invention consists in providing a bucket that may be used in swift flowing water, along the ocean beaches and in any and all places where materials are to be handled in commercial quantities and at low cost.

35 A further object of my invention consists in providing a drag line bucket that is supported within a suitable frame and the bucket being so

secured to the frame in an articulating manner the entire weight of the bucket and frame may be placed upon the bucket during the filling of the same.

40 And a still further object of my invention consists in so constructing a drag line bucket having lines associated therewith that may be used as haul back lines, as pulling lines, as sling lines and as trip lines, all of the lines may be handled from a common prime mover and with a minimum of labor and effort.

45 A still further object of my invention consists in providing a bucket that may be filled and one in which the filled material may be safely transported through water or through the shore line of the sea without loss of the material placed within the bucket during the filling operation of the same.

50 A still further object of my invention consists in so constructing the frame and the supports therefor that the load may be transferred from the wheels of the supports directly to the bucket at the will of the operator.

55 With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a perspective side view of the assembled device shown in position for the filling of the bucket.

Fig. 2 is a side view of the assembled device illustrating the same as being supported upon the side wheels and illustrating all of the doors of the bucket as being closed, in which position I have found best results are to be obtained when the bucket is returned by the haul back line to the point of loading.

Fig. 3 is a top plan view of the mechanism illustrated in Fig. 2 and the bucket in the position relative to the frame as illustrated in Fig. 2.

Fig. 4 is a fragmentary detailed side view of an adjusting means for predetermining the relative location of the bucket to the frame during the filling operation. This adjusting means predetermines the amount of thickness of the slice of the material that is to be crowded into the bucket during the filling operation.

I preferably form my device of structural side frame members 1 and 2. These side frame members may be made hollow and air-tight. It

is fundamentally important in devices of this kind to provide suitable means for predetermining the weight of the frame. Where heavy digging is to be encountered as cement gravel, it is necessary to make the frame heavy. Where the digging is to be carried on in slush material or in unpacked material to facilitate the operation of the device it may be necessary to make the frame light through buoyancy. To accomplish the predetermination of the frame weight I provide a filler plug 3A that may be placed in the high point of the frame assembly as in the cross yoke 9 that is preferably made hollow and its interior communicating with the interior of the side frames 1 and 2. I provide one or more bleeder cocks 4 on the underside of each of the side frame members 1 and 2; through which means the frame may be filled or partly filled with a liquid. This provides simple and efficient means for predetermining the weight that may be placed upon the bucket during the filling operation or to provide means for lessening the weight that is to be applied to the bucket during the filling operation where the same is being operated over unstable ground.

Supporting wheels 5, here shown as four in number, are rotatably disposed at either side of the assembled device. The front pair of wheels are supported in suitable journals upon stub shafts 6. The rear pair of wheels are journaled upon an axle 15A that extends transversely of the frame. In some instances it may be found desirable to place drums 7 at the opposite ends of the frame to facilitate the transporting of the device across unstable ground. These drums are adjustably secured at their respective ends to the frame by any suitable brackets 8. Where the device is being used in a stable media as hard pan or cement gravel it may be found desirable to remove the drums and the brackets from the device.

The side frame members 1 and 2 are secured together by suitable cross supports. I place a cross support 10 at the rear of the device and the same is made sufficiently strong to place a support 11 thereupon that has a block or eye 12 secured thereto through which the haul back line 13 passes. A cross yoke 14 is secured between the front end of the side frame members. The cross yoke 14 preferably extends upwardly from the top side of the front end of the side frame members in sufficient amount to permit a free passage of material therethrough and to permit the same to flow directly into the bucket during the digging and filling operation. A third cross yoke 9 upwardly extends from the side frame members 1 and 2 and the same is disposed between the cross frame members 10 and 14.

A bucket 15 is disposed between the side frame members 1 and 2. The bucket is hinged at its rear end to a cross support, as the axle 15A to which one of the pair of supporting side wheels are journaled. The bucket may be hingedly secured to any suitable cross brace that may be provided for that or for other purposes. The front end of the bucket is floating. The front end of the bucket normally rides upon any suitable supports as camming surfaces that may be utilized for the positioning of the cutting lip of the bucket during the digging and filling operation of the same. A filler door 16 is hingedly secured to the front end of the bucket. This door is hinged to the body of the bucket by any suitable hinging means as through the action of a hinge pin 18 that runs transversely of the

bucket. The ends of the hinge pin pass through suitable journaling ears secured to the sides of the bucket. Links 19 are disposed at either side of the bucket. The rear end of each of the links 19 is secured to a bridle 20. The front end of each of the links is secured to the door 16 between the hinged end of the door and the lip end 21 of the door and as the bridle is manipulated through the haul back line 13 and the trip line 22 the door may be opened or closed. The front ends of the links 19 are secured to the door by any suitable hinging connection as through the medium of a shaft 23. The lower ends of the bridle 20 are inwardly turned to form arms 20A that are disposed at right angles to the side arms 15 of the bridle and a cam 20B is secured thereto. A lug 30 outwardly extends from the edge of each arm of the bridle adjacent the journaled ends of the arms, to which the links 19 are hingedly secured.

The device is pulled to the point of loading by application of pulling pressure to the haul back line 13. When the device has been pulled thereby to the point of loading, pressure is then applied to the trip line 22 and the bridle 20 is raised into the position as illustrated in Fig. 1. A chain 24 is secured upon its one end to a cross bar 25 that is secured transversely of the side bars of the bridle 20. The oppositely disposed end of the chain 24 is secured to the venting door 26. The venting door 26 is hingedly secured to a chest 27 that upwardly extends from the rear end of the bucket 15 and as the bridle is pulled forward an opening 28 is created in the top side of the chest, this prevents the trapping of the air or water in the bucket in the filling operation. A further movement of the bridle 20 is limited by the links 19 raising the filling door 16 to the limit of its opening. One end of each of the side bars of the bridle 20 is hingedly secured to any suitable hinge pin 29 that is journaled within blocks 20c that upwardly extend from the top side of the side frame members 1 and 2. The haul back line 13 is secured upon its one end to a link 31. The link 31 is hingedly disposed between the side arms of the bridle 20 and an adjustable stop 32 is disposed upon the haul back line and engages the eye 12 through which the haul back line passes and thereby applies the pulling pressure directly to the cross support 10 disposed upon the rear end of the frame. Simultaneously with the application of pulling pressure to the haul back line 13 the doors 16 and 26 respectively are closed.

When it is desired to load the bucket the trip line 22 that is secured upon its one end to the link 31 and upon its opposite end to any drum, nigger or other pulling winch has sufficient pulling pressure applied to raise the frame independently of the bucket and to place the weight 60 of the frame upon the bucket. A pulling pressure is then applied to the lines 33 and 34. The lines 33 and 34 pass through suitable blocks, or eyes 35 and are secured upon one of their ends to the bucket as illustrated in Fig. 1 at 36. The hitching of the lines to the bucket is made at a higher point than that of the eyes 35 through which the same pass. The hitch being made at a higher point has a tendency to raise the frame and to simultaneously apply a crowding action 70 to the bucket by the throwing of the combined weight of the frame upon the bucket assembly. The amount of crowding action may be predetermined by the selective locating of a cross bar 37 within stop supports 38 that are disposed 75

within the oppositely disposed sides of the cross support 9. The cross bar 31 by being selectively positioned between the supports 38 predetermines the depth to which the bucket will dig. 5 It will be seen that as the bridle 20 is raised, rotation of the cam 20B will cause the front end of the bucket to be lowered. The cutting edge 39 of the bucket is made of suitable hardened material and the same is reinforced by spaced 10 teeth 40 that are disposed upon the upper side of the cutting lip of the bucket.

Where the device is to be used in extremely soft material it may be found desirable to place 15 runners 41 and 42 at either side of the frame and to run the same longitudinally of the frame and adjacent the pairs of wheels 5 disposed upon the oppositely disposed sides of the frame. It may even be found desirable where runners of 20 this kind are used to remove the wheels 5 from the frame. The runners 41 and 42 are secured at their respective ends to the ends of the frame members 1 and 2 and extend in spaced relation with the under side of the side frames.

After the bucket has been filled pulling pressure is then released upon the trip line 22 to thereby permit the doors 16 and 26 to close through the action of gravity. If for any reason 25 the front door fails to close the same may be forcibly closed by pulling the haul back line 13. 30 When the bucket has been pulled to the point of dump by the main haul lines 33 and 34 it may then be hoisted by sling lines 43 and 44, 45 and 46 and be then conveyed by over-head line to the point of dump. When the lines 45 and 46 35 are released and the door 16 opened by exerting a pull on the line 22 the materials within the bucket are permitted to flow therefrom out of the filling door 16. To prevent a partial vacuum within the bucket during the dumping operation the trip line 22 may be manipulated and the doors 16 and 26 be opened to their full capacity.

I preferably extend the rear axle beyond the 40 wheels at either end in order that the extended portion of the axle may be made to ride supporting members that are provided at the dump to support the device. In doing so the front of the device will be permitted to follow into the hopper or other receiving space and the loaded device will assume a longitudinal vertical position. 45 Simultaneously therewith the trip line may be actuated to open the respective doors to permit the outward free flowing of the contents of the bucket. If substantial speed is imparted to the 50 bucket at the time of arrival at the dump the material in the bucket will be shocked at the sudden up ending of the bucket and the same will be violently thrown from the bucket to thereby free the bucket from its contents. The application of 55 pulling pressure to the haul back line returns the bucket to its normal horizontal position.

While I have here shown my device as being largely made from structural shapes welded together, I do not wish to be limited to this form of construction as the device may be made of any 60 suitable material and of any suitable shape and dimension to meet the requirements of the service to which the same is to be put.

What I claim is:

1. In a device of the class described, the combination of a hollow fabricated frame, means for predetermining the weight of the frame, wheels

disposed at either side of the frame, and drums disposed at either end of the frame, a bucket disposed within the frame, the rear end of the bucket being hingedly mounted relative to the frame, the front end of the bucket being mounted within the frame and adjustably supported upon camming surfaces, power means for manipulating the cams and for raising and lowering the bucket within the frame, doors disposed at either end of the bucket, power means for opening the doors, means 10 for predetermining the crowding action on the filling end of the bucket while the same is being filled, and a main haul line secured to the bucket, a haul back line secured to the frame, a trip line 15 and hoisting lines.

2. In a device of the class described, the combination of a frame, means for filling and draining the frame with a fluid, wheels and a runner associated with the frame and disposed at either side of the frame, roller supports removably disposed at either end of the frame, a bucket disposed within the frame, one end of the bucket being hingedly supported and the other end of the bucket being floating, means for power lifting the floating end of the bucket, doors disposed at 25 either end of the bucket, means for power actuating the doors, each independently, a haul back line, a main drag line, a trip line and lifting lines associated with the assembly.

3. In a device of the class described, the combination of a fabricated frame, cross supports connecting the side frames together, said frame elements being hollow and air tight, means for filling and draining the interior of the frame, rolling supports disposed at either end and at 35 either side of the frame, a bucket hingedly disposed between the side frame members, a filler door disposed at one end of the bucket and a venting door disposed at the other end of the 40 bucket, means for crowding the filling end of the bucket into the material to be dug, means for actuating each of the doors into open and into closed position, and hauling and lifting lines associated with the assembly.

4. The combination in a digging and conveying 45 device comprised of an air tight fabricated frame, means for admitting liquids into the frame and for draining liquids therefrom to predetermine the weight of the frame, a bucket hingedly disposed within the frame, means for supporting 50 the bucket within the frame, means for placing the combined weight of the frame upon the bucket and means for pulling the assembly either forward or backward and for lifting the same in a vertical direction and for tilting the same 55 while lifted.

5. In a device of the class described, the combination of a fabricated frame, means for predetermining the weight of the frame, a bucket hingedly supported with the frame upon one of 60 its ends, power means for tilting the floating end of the bucket relative to the frame, rolling supports for the frame, doors disposed at either end of the bucket, power means for opening the doors, a main power line secured to the front end of the 65 bucket, a haul back line indirectly secured to the rear end of the frame, a trip line for tilting the bucket and sling lines for raising the assembly and for dumping the bucket.
